FIG. 1 is a front and bottom perspective view of a telephone receiver cover showing my new design;

FIG. 2 is a rear and top perspective view thereof;

FIG. 3 is a front elevation view thereof;

FIG. 4 is a side elevation view thereof, the opposite side being a mirror image thereof; and

FIG. 5 is a cross-section taken on line 5—5 of FIG. 1. My design is chiefly to be used as a design for a telephone receiver cover.

I claim:

The ornamental design for a telephone receiver cover, substantially as shown and described.
